Letters Patent No. 1,265, Dated 17th July 1766.

Design for a Chandelier

The shaded areas referred to in these letters Patent and making part of the same.

To all whom it may concern:

Be it known that I, J. J. Tricker, of Boston in the County of Suffolk, and State of Massachusetts have originated and produced a new Design for a Chandelier, of which the following is a full and clear description, reference being had to the accompanying drawing making part of this Specification.

In the Design represented by the drawing, a vertical stem a , has lateral arms or branches b , upon the ends of which are supported fluted lamps c , the whole ornamentally configured as seen.

I claim the Design for a Chandelier as shown and described.
